UNITED STATES PATENT OFFICE

2,504,699

TUBE PROTECTIVE CIRCUIT

Edward C. Kluender, Schenectady, N. Y., assignor
to General Electric Company, a corporation of
New York

Application April 27, 1946, Serial No. 665,365

5 Claims. (Cl. 179—171)

1

My invention relates to protection of electron discharge devices and more particularly to protecting electron discharge devices used in power conversion apparatus from excessive heating due to mistuning, short circuits, or other events.

In the application of electron discharge devices to energy converting apparatus such as oscillators, power amplifiers and the like, the power dissipated in the device, and hence the temperature rise thereof, is critically dependent on the load adjustment and circuit conditions. In class C radio frequency oscillators and amplifiers, for example, mistuning of the output circuits such as might result from a short or open circuit in the antenna or other load connected thereto causes the radio frequency component of space path voltage greatly to decrease, thereby causing a greater average space path voltage during the conduction time of the device. The energy dissipated therein is accordingly increased and, unless steps are taken immediately to disconnect the space path potential source, destruction of the device will result.

It is an object of this invention to prevent accidental overload of electron discharge devices in energy converting equipment.

It is a further object of this invention to provide improved means to prevent overload of electron discharge devices in energy converting equipment, which means does not interfere with the normal functioning of the equipment for its intended purpose while at the same time is capable of immediately interrupting overload thereof or producing a suitable signal when dangerous operating temperatures are approached.

Yet another object of this invention is to provide overload protection for an electron discharge device used in power conversion equipment in a manner simple of construction and reliable in operation and readily applicable to various types of power conversion equipment.

The novel features characteristic of my invention are set forth with particularity in the appended claims. My invention itself, however, both as to its organization and method of operation may best be understood by reference to the following description taken in connection with the accompanying drawing in which Fig. 1 shows one method whereby electron discharge devices may be overloaded and Fig. 2 shows an embodiment of my invention capable of preventing this overload.

By way of illustration, the method by which class C radio frequency oscillators and amplifiers may be accidentally overloaded will first be described with reference to Fig. 1. It will be understood, of course, that this invention is applicable to protection of electron discharge devices used in power converting equipment generally and is not limited to this particular application.

2

In the figure, curve A represents the control electrode voltage applied to an electron discharge device operating in the class C condition. In this case the negative unidirectional bias voltage OY maintains the control electrode voltage E_g below the cut-off bias OX except during a small portion of the positive portion of each cycle. The corresponding cathode-anode space path voltage is shown in curve B. This voltage consists of a sine wave voltage of radio frequency E_p superimposed on the unidirectional space path voltage OZ. The radio frequency component of this voltage is 180° out of phase with the control electrode voltage so that minimum cathode-anode voltage exists at the instant of maximum control electrode voltage. Curve C shows the cathode-anode space path current of the electron discharge device. This current is zero so long as the control electrode voltage is less than the cut-off bias value and has a sharp peaked wave shape I_p when the bias is above cut-off.

The energy dissipated within the electron discharge device is determined by the integrated product of instantaneous space current flow and space path voltage. These two values under normal conditions of operation are shown in the cross sectioned areas of Fig. 1. It should be noted that neither space path current flow nor space path voltage drop of itself is a measure of this energy as a high value of one of these factors, accompanied by a low value of the other, may not involve any increase in energy to be dissipated. Hence neither space current flow nor space path voltage may be used to indicate the energy dissipated within the electron discharge device. It should further be noted that the average value of space path voltage is no indication of the energy dissipated within the electron discharge device inasmuch as the space current flows only during a portion of the cycle, this portion corresponding to a period of minimum space path voltage. Hence, average space current flow cannot be combined with average space path voltage to measure the energy dissipated within the electron discharge device.

If maladjustment of the tuned circuits, a change in load impedance (such as an antenna short circuit or open circuit), or other event reduces the alternating component of the space path voltage across the electron discharge device, the space path voltage during the instant current flow occurs is increased as shown in the dashed curve labeled E_p' , Fig. 1. This increased space path voltage causes a corresponding increase in space path current during the period of current flow as shown in curve I_p' . These two effects combine to cause an exaggerated increase in the energy dissipated within the electron discharge device and, if the change is great, will quickly cause the device to overheat and be destroyed. Often this

overload is much greater than would be anticipated from the waves shown in Fig. 1 by reason of distortion of the wave shapes and phase relations of the various voltages and currents.

Reference will now be made to Fig. 2 which shows a class C radio frequency amplifier protected in accordance with the principles of this invention. In the figure, an electron discharge device is indicated at 1 having a heated cathode, an anode, a control electrode, and a screen grid electrode. Radio frequency control electrode voltage is applied to this device from driver 2 through coupling condenser 3. Unidirectional control electrode bias is derived from voltage source 27 through radio frequency choke coil 25. The voltage of source 27 is chosen to produce sufficient negative potential at the control electrode of device 1 to cause that device to be biased to cut-off except during the desired portion of the radio frequency control electrode voltage curve. Condenser 26 bypasses radio frequency currents about source 27. Cathode-screen electrode space path voltage for device 1 is supplied from unidirectional voltage source 6 through relay contacts 7. Condenser 9 bypasses to ground any radio frequency voltage appearing at the screen electrode. Cathode-anode space path voltage for device 1 is supplied from unidirectional voltage source 6 through relay contacts 8 and radio frequency choke coil 10. It is the purpose of the latter device to prevent source 6 from bypassing radio frequency voltages from the anode to ground.

The anode of device 1 is coupled by condenser 11 to a utilization circuit shown generally at 12. This circuit consists of a resonant circuit having a load such as a radiating antenna coupled to it. For purposes of explanation, it is shown as an approximate equivalent circuit comprising condenser 13, inductance 14, and resistance 15. Under normal operating conditions, the resonant frequency of condenser 13 and inductance 14 corresponds to the frequency of the applied control electrode voltage and the value of resistance 15 is sufficiently large to produce only a limited effect on this frequency. As explained above, any maladjustment, short circuit, or open circuit will cause device 12 to be mistuned, thereby causing a decrease in the impedance thereof and reducing the radio frequency voltage at the anode of device 1. This correspondingly increases the losses within that device.

The protective circuit for device 1 includes relay 16 and electron discharge device 17. It is the purpose of the latter device to produce a unidirectional voltage varying in accordance with the alternating component of space path voltage of device 1. This is accomplished by coupling part of the voltage across utilization device 12 to device 17. This coupling is provided by the capacitive voltage divider comprising capacitors 18 and 19 which applies a predetermined portion of the voltage across device 12 to the series circuit including capacitor 20, device 17, and the parallel combination of resistance 21 and capacitor 22. Resistance 23 provides a return path for current flow in device 17.

Resistance 21 and capacitor 22 are chosen to have a time constant that is large with respect to the period of the radio frequency waves across utilization device 12. This causes a substantially constant voltage to appear across resistance 21, the value of this voltage being determined by the radio frequency voltage across device 12. The polarity of this voltage is such as to cause the

cathode of device 17 to become positive with respect to ground potential.

A relay, shown generally at 24, is provided to disconnect the anode and screen grid electrodes of device 1 from source 6. Current flow in coil 16 opens contacts 7 and 8. Operating coil 16 is connected between the cathode of device 1 and the cathode of device 17 so that the current flow therethrough depends on the difference between the relative voltage at these points. When this difference exceeds a predetermined value in either direction, the relay operates, thereby opening contacts 7 and 8 to disconnect source 6 from the various electrodes of device 1 and preventing further space path energy flow to device 1.

When an increase in average cathode-anode space current flow in device 1 takes place, the voltage drop across resistance 4 is accordingly increased. This voltage drop is substantially constant by reason of the smoothing action of capacitor 5. However, if a corresponding increase in radio frequency output voltage takes place, the voltage at the cathode of device 17 will be raised, thereby preventing the increased current flow in operating coil 16 that would otherwise be associated with the increased space current flow. However, if no increase in radio frequency output voltage takes place, the potential of the cathode of device 17 will remain constant and the greater cathode voltage at device 1 will cause increased current flow in coil 16, thereby causing relay 24 to operate. Inasmuch as the energy dissipated in device 1 is dependent on the relative values of space current flow and radio frequency voltage output, it is evident that this operation of relay 24 protects device 1 when overload is imminent while permitting load increases that do not involve such overload.

It will be noted that the cathode-screen electrode space current flow in device 1 flows through resistance 4 and influences performance of relay 24 accordingly. Actually, this current is so small compared to the cathode-anode space path current that the effects so produced are not significant insofar as relay 24 is concerned.

If, through some changes in the amplifier circuit or load, the radio frequency output voltage of device 1 is decreased, the potential at the cathode of device 17 is correspondingly reduced. If this change is accompanied by a reduction in space current flow of sufficient magnitude to prevent overheating of device 1, a corresponding reduction in the cathode potential of the latter device will take place and no increased current flow through coil 16 will cause operation of relay 24. On the other hand, if the space current flow in device 1 is not reduced, the voltage at the cathode of device 1 will remain the same and relay 24 will operate, thereby preventing the tube damage that would otherwise be associated with this condition.

In general, I prefer to choose resistance 4 to have the smallest resistance possible thereby reducing the power loss associated with the presence of this resistance in the space path current path of device 1. This power loss, as well as the impedance effects associated with condensers 18, 19, 20, and 22, resistances 21 and 23, and device 17, may be even further reduced by actuating relay 24 from a separate amplifier provided for the purpose. Furthermore, the effects of the control circuit across utilization device 12 may be reduced by amplifying the radio frequency voltage before application to device 17.

If desired, time delay apparatus may be pro-

vided in connection with relay 24 even further to improve the performance of the circuit. In this case, the time delay is made to correspond with the thermal time constants of the elements of device 1 so that the relay operates only after a time delay determined by the ability of device 1 to stand short time overloads.

If desired, relay 24 may be a single pole relay connected only to interrupt the supply of screen electrode potential to device 1, choke coil 10 being directly connected to the positive terminal of source 6. In this case, device 1 will be protected from overload by loss of screen electrode voltage, an event sufficient to avoid overheating in most cases. Alternatively, relay 24 may be connected to actuate an alarm device, such as a bell or light, thereby to warn the operator of the equipment and enable him to take appropriate steps to prevent damage. It will, of course, be apparent to those skilled in the art that operation of relay 24 may be made to cause these events as well as many others without departing from the true spirit and scope of this invention.

The term "energy converting equipment" or "energy conversion system" as used herein refers to equipment wherein an electron discharge device is used as a means of converting energy of one type, as for example, unidirectional voltage, to another type, as for example alternating voltage, and characterized by the fact that the power dissipated in the electron discharge device is determined by the difference between the applied energy of one type and the output energy of another type.

While I have shown and described my invention as applied to a particular system of connections and embodying various devices diagrammatically shown, it will be obvious to those skilled in the art that changes and modifications may be made without departing therefrom. In particular, the methods described herein may be used to protect electron discharge devices in circuits other than the class C radio frequency amplifier shown, such other circuits including, for example, class C oscillators, class A oscillators and amplifiers, and class B oscillators and amplifiers. I therefore aim in the appended claims to cover all such changes and modifications as fall within the true spirit and scope of this invention.

What I claim as new and desire to secure by Letters Patent of the United States is:

1. In combination, a high frequency electron discharge amplifier having an output circuit coupled for energy transfer at said high frequency to a load impedance, means to derive a first unidirectional potential proportional to the peak voltage at said frequency developed across said impedance, means to derive a second unidirectional potential proportional to the average space current in said amplifier, relay means actuated by said potentials when the difference between them exceeds a predetermined value, and means controlled by actuation of said relay to limit said space current to a safe value.

2. In combination, an electron discharge amplifier having input and output circuits, means for supplying oscillations to said input circuit, a resonant load device coupled to said output circuit and tuned to the frequency of said oscillations, peak voltage rectifying means supplied with oscillations from said load device for developing a first unidirectional voltage, resistance means common to said input and output circuits and shunted by a low capacity at said frequency for developing a second unidirectional voltage, and

relay means responsive to said voltages for removing operating potential from said amplifier when the difference between said voltages exceeds a predetermined value.

3. In an energy conversion system, an electron discharge device having an anode-cathode space path, means to impress anode operating potential on said device, a utilization device, means to supply power from said space path to said utilization device, means to produce a first unidirectional voltage which is a function of the current in said space path, means to produce a second unidirectional voltage which is a function of the voltage appearing across said utilization device, a relay having an operating coil, means for impressing said voltages on said coil in opposing polarity, said relay being arranged to be actuated only when the difference between said voltages exceeds a predetermined value, and means controlled by actuation of said relay to limit said current to a safe value.

4. In an energy conversion system, an electron discharge device having a cathode, a control electrode and an anode, means to apply oscillations to said control electrode, means to impress anode-cathode operating potential on said device, a utilization device, said last device including a resonant circuit normally tuned to the frequency of oscillations from said first means, means connecting said utilization device to said discharge device, means to produce a first unidirectional voltage proportional to the average value of space current flow in said discharge device, rectifying means energized from said resonant circuit to produce a second unidirectional voltage proportional to the voltage across said circuit, a relay, means for impressing said voltages on said relay in opposite polarity, said relay being arranged to be actuated by said voltages only when the difference between them exceeds a predetermined value, and means controlled by actuation of said relay to limit said space current to a safe value.

5. In combination, an electron discharge device having a cathode, an auxiliary electrode, and an anode, means to impress anode-cathode operating potential on said device, means to impress operating potential on said auxiliary electrode, a utilization device, means to cause said discharge device to supply converted energy to said utilization device, means to produce a first unidirectional voltage proportional to the converted energy supplied to said utilization device, means to produce a second unidirectional voltage proportional to the average value of anode-cathode space current flow in said discharge device, and means responsive to the difference between said voltages to disconnect said second means from said auxiliary electrode when said difference exceeds a predetermined value, thereby to limit said space current.
